UNITED STATES PATENT OFFICE.

LOUIS IVES MILLER BIGBY AND JAMES ROBERT MEIKLE, OF LONDON, ENGLAND, AS
SIGNORS TO THOMAS MEADOWS & CO., LIMITED, OF LONDON, ENGLAND, A CORPORA-
TION OF GREAT BRITAIN.

PACKING CASE.

Application filed October 19, 1921. Serial No. 508,786.

To all whom it may concern:

Be it known that we, LOUIS IVES MILLER BIGBY and JAMES ROBERT MEIKLE, both subjects of the King of Great Britain, and both residing at 35 Milk Street, in the city of London, England, have invented new and useful Improvements in Packing Cases, of which the following is a specification.

This invention relates to the construction of packing cases, and more especially to those which are employed for containing goods to be shipped, or sent by rail, post, or carrier, and generally in instances where it is desirable to prevent the contents being stolen, or tampered with, during transit. This invention provides improved cases of the aforesaid kind which, being very strong, afford considerably greater protection against theft, or tampering, than do ordinary cases and correspondingly lessen insurance charges, whilst they are capable of being economically manufactured and do not occupy more space than is occupied by ordinary cases; so that their use does not involve any increased charges for freight. With ordinary packing cases made of boards arranged side by side, and usually strengthened by iron hooping, the contents are frequently stolen, or tampered with, by removing one of the boards, after withdrawing the nails by which the metal bands are secured at the part where they cross the board, and then abstracting some of the contents through the uncovered space and, after replacing the board and the band and reinserting the nails, the fact that the case has been tampered with is not noticeable. It has been proposed to overcome this objection by making the case in two parts, an outer part and an inner part constituting an inner box, or lining, fitting into the outer part, the boards of these parts being arranged so that the edges where the boards of the one part meet do not coincide with the edges where the boards of the other part meet. The present invention relates to this latter description of cases and has for its object to provide cases which are very secure against theft and tampering.

According to this invention the inner and outer parts are secured together by nails which are passed transversely through the boards of the said parts from the inside of the inner part and are clenched at

their ends which protrude through the outer boards so that the heads of the said nails prevent them being withdrawn from the outside of the case. Waterproof, or damp-proof, material may be placed between the inner and outer parts of the case—and metal strips, or bands, may be placed between the inner and outer parts so that they lie across the meeting edges of the boards of the outer part, these strips, or bands, preferably being unattached to the said boards.

We will describe with reference to the accompanying drawing how this invention may be performed.

Figure 1 is an isometrical projection shewing a case of the kind aforesaid provided with the improvements in accordance with this invention some of the boards of the outer part being removed. Figure 2 is a transverse section on the line $\alpha\alpha$ Figure 1 and Figures 3 and 4 show details hereinafter described while Fig. 5 is a broken perspective illustrating the use of water-proofing material between the inner and outer members of the case.

The case to which this invention is applied has the boards a of the inner part arranged so that they run at right angles, or diagonally, to the boards b of the outer part, the boards a and b of the respective parts being secured together by nails c driven from the inside of the inner part through the boards of the two parts and clenched at their ends which protrude through the outer boards b so that the heads of the nails will prevent them being withdrawn from the outside of the case and it will be found very difficult, or impossible, to remove an outer board, or to tamper with the case without the fact of such removal, or tampering, being at once apparent. Figure 3 shews portions of an inner board and an outer board thus secured by clinch nails c these being driven as aforesaid from the inside of the box and their ends being turned back, or clenched at the outside of the case as shewn at c^2 , thus ensuring that no board can be removed without cracking, or breaking, it and so making tampering with the case apparent.

We preferably place metal strips, or bands, d , in such positions between the boards a and b constituting the inner and outer parts of the case, so that the said

strips, or bands, *d* will constitute protection against the boards *b* of the outer part of the case being cut, or sawn, through, whilst, if the cutting, or sawing, should be attempted, the fact that the case has been tampered with will become at once apparent. The said strips, or bands, *d* are arranged in such positions that they cross the lines of the joints between the boards *b* of the outer part of the case and therefore also the line of any cut, or sawing, which would be attempted for the purpose of abstracting any of the contents from the case. The said metal strips, or bands, *d*, are preferably not nailed, or otherwise fixed, to the boards, as, by leaving them unfixed, cutting, or sawing, is rendered still more difficult. It is preferable that the ends of the said strips, or bands, *d* should not come up to the edges of the boards, where they would be exposed at the exterior of the case, so as to guard against the said strips, or bands *d* being withdrawn endwise.

To guard against the lid, or cover, (or other side, or part, of the case, where the boards overlap the edges of another side, or part,) being prized up and removed, we provide protectors consisting of strips, or short lengths, *f* of metal one end of each of which, (presuming, for example, that the lid, or cover, is being so secured) is inserted, and secured, by clinched nails, as illustrated at *c*³, or otherwise, between the boards *a* and *b* of the inner and outer parts of the sides of the case from the edges of the said sides against which the lid, or cover, abuts when in place. Figure 4 shows part of an upper board of the outer part of the case with an aforesaid strip, or short length, secured to it. Each of the said strips, or bands, *f* is bent, at *f*², over the said edge of the said board and nailed, or screwed, down thereto. The upstanding parts of the said strips, or bands, (after the lid, or cover, is put in place) are turned up over the edges (as at *f*³) and a sufficient distance over the lid, or cover, of the case (as at *f*⁴) and the parts so turned over are, in each instance, nailed through by nails *c*⁴ which pass through the lid, and through the part of the strip, or band, *f*² (which, as aforesaid, lies over the edge of the body of the case) and into the edge of the sides beneath. The parts *f*⁴ of the strips, or bands, *f* which pass up over the edge of the lid, or cover, prevent a tool being introduced so as to gain access to the securing nails *c*³ for levering up the lid, or cover.

If desired the cases can be made water-proof, or damp-proof, by inserting water-proof, or damp-proof material, (such as tar lining, for instance) between the parts of the case. This may be effected, for example, as shown in Fig. 5 which illustrates in perspective a fragment of a case con-

structed in accordance with this invention, having water-proof, or damp-proof, material *g* between the inner boards *a* and the outer boards *b*. The water-proof, or damp-proof material on the sides, top and bottom members of the case project any suitable distance beyond the inner boards *a* and the water-proof, or damp-proof, material on the end members project beyond the outer boards *b* and is bent onto the edges of the said boards as shown at *g*¹, so that when the side, top and bottom members are nailed to the end members, the projecting portions of water-proof, or damp-proof, material on the sides, top and bottom members will lie against the bent-over portions on the edges of the end members and the pressure caused by nailing will ensure a water-proof, or damp-proof, joint.

The joints of the cases in accordance with this invention will not be liable to open as the arrangement of the boards and the aforesaid way in which they are secured together will prevent warping.

In constructing cases in accordance with this invention it is preferred to first make the side, top and bottom elements with inner and outer boards secured as aforesaid (with the bands, or strips, *d* therebetween and the bands, or strips, *f* in position) and then securing these elements together which may be effected in the ordinary manner of case construction.

Although we have described a case made with but one inner part, it will be understood that more than one inner part can be used if desired.

What we claim is:

1. A wooden packing case comprising two ply walls, the boards of one ply having their meeting edges extending in a direction at an angle to the meeting edges of the boards of the juxtaposed ply, and metal straps arranged between the two plies and at an angle to the meeting edges of the boards of the outer ply.

2. A wooden packing case comprising two-ply walls, the boards of one ply having their meeting edges extending in a direction at an angle to the meeting edges of the boards of the juxtaposed ply, and metal straps arranged and freely engaged between the two plies and at an angle to the meeting edges of the boards of the outer ply.

3. A wooden packing case comprising two-ply walls, the boards of one ply having their meeting edges extending in a direction at an angle to the meeting edges of the boards of the juxtaposed ply, and metal straps arranged between the two plies and at an angle to the meeting edges of the boards of the outer ply and being of less length than the width of the wall transversely to the boards of the outer ply.

4. The combination with the construction

specified in claim 1, of metal corner straps secured to the inner face of the outer ply of the wall and projecting beyond the outer edge of the wall to afford means for anchoring the said wall to the margin of the meeting wall of the box.

5. The combination with the construction specified in claim 1, of nails driven through both plies from the inner face of the box 10 wall and clinched on the outer face of said wall, together with water-proofing material arranged between the inner and outer plies of the wall.

In testimony whereof we have signed our names to this specification in the presence ¹⁵ of subscribing witnesses.
